UNITED STATES PATENT OFFICE.

JOSEPH WADLEIGH, OF MILKS GROVE, ILLINOIS.

MECHANISM FOR OPERATING BALING-PRESSES.

SPECIFICATION forming part of Letters Patent No. 405,286, dated June 18, 1889.

Application filed December 15, 1888. Serial No. 293,675. (No model.)

To all whom it may concern:

Be it known that I, JOSEPH WADLEIGH, a citizen of the United States, and a resident of Milks Grove, in the county of Iroquois and 5 State of Illinois, have invented new and useful Improvements in Mechanism for Operating Baling-PresSES, of which the following is a specification, reference being had to the accompanying drawings, illustrating the invention, in which—

Figure 1 is a longitudinal elevation of my invention, the press-box being shown in section; Fig. 2, a top or plan view of Fig. 1 with the baling-press removed; Fig. 3, a horizontal 15 section of Fig. 1 on line X; Fig. 4, a plan of the arms and pitman-connections removed from between the gear-wheels.

The nature of this invention will be fully comprehended from the following detailed description.

A represents the top portion of a foundation for the support of the mechanism herein-after described. At one end of this foundation is affixed a frame with suitable supports 20 to serve as bearings for the shaft of a worm-gear Q, which may be driven by any suitable power, but preferably by the tumbling-rod of a horse-power, which is to be attached to the outer end R of the shaft of the worm-gear in 25 the ordinary manner of making like connections. Secured to said foundation A on both sides of the gear-wheels B B are standards D, and in the upper ends of the same are formed 30 bearings C for the separate shafts of the separate gear-wheels B to rotate in, the centers of said shafts being on the same axial line. The gear-wheels B are provided on the inner portions of their peripheries each with a like number of cogs, and the cogs on each gear-wheel 35 engage alike the worm-gear, so that when they are driven by said worm-gear each gear-wheel will have a like motion, the form of the cogs on the wheels B being such as properly to mesh with said worm-gear. When the mechanism 40 is employed for pressing hay, it is very desirable that the wheels B be placed so closely together as will just permit the pitman to operate between them, that hay may be kept from interfering with the arms which drive 45 the pitman.

The inner faces of the wheels B are coun-

tersunk, as at F F, to provide room for two arms G, which at their inner ends are hung to pivots projecting in centrally from said gear-wheels, as shown at H H. The outer 55 ends of the arms are hung to a cross-pin Y in the inner end of the pitman E, as more clearly shown in Figs. 3 and 4. The pin Y at each end projects beyond the arm G and into semi-circular recesses Z Z in the inner faces of the 60 gear-wheels B, that the ends of the recesses may engage the said pin and drive the pitman, which is jointed to the rod of the plunger to the press. The latter is shown at I, the plunger at J, and the hay to be pressed at K, 65 the press being shown in longitudinal section at Fig. 1, and being of ordinary construction. The advantage of this construction is, that remittent reciprocating motion is attained by very compact and simple means, in which, by 70 enlarging the construction, an increased length of stroke to the pitman is attained, and by increasing the motion of the worm-gear the intermitting period is shortened without materially changing the effect of the plunger. 75

The operation is as follows: The wheels B are in such position that when the pitman E is brought to a level with their axes, and when the left-hand ends to the semicircular slots Z Z have brought the pin Y to a point which projects the pitman the greatest distance outward to force the plunger J against the hay K or other material to be pressed, the further turning of the wheels B will permit the pin Y to rebound back in the recesses Z by the 80 elasticity of the pressed hay, and consequently there will be a suitable interval before the same ends of the recesses again drive the pin Y for supplying the press with a charge of hay, notwithstanding the wheels B have a 85 continuous motion.

Practically it makes no difference in the working of the press as to which way the wheels B are turned. In one case the recesses Z will lie above the bearings C when the pin 95 Y rebounds, and in the other case they will lie below them.

I claim as new and desire to secure by Letters Patent—

In mechanism for operating baling-presSES, 100 the separate gear-wheels B B, mounted on separate shafts having a common axial line,

and provided centrally on their inner sides with pivots H, recesses F, and semicircular recesses Z, in combination with arms G, hung to said pivots and lying in recesses F, a pitman E, provided with a cross-pin Y, projecting through the opposite ends of said arms and into recesses Z, means for connecting the

worm-gear Q, meshing with the gear-wheels, and the shaft of the worm-gear provided with means for connecting it with suitable power, as and for the purpose specified.

JOSEPH WADLEIGH.
